ABSTRACT OF THE DISCLOSURE

This invention relates to novel substituted tricyclic compounds of the formula

wherein R is alkyl having from 1 to 6 carbon atoms, X is selected from the group consisting of hydrogen, alkyl having from 1 to 5 carbon atoms, alkenyl having from 3 to 5 carbon atoms, alkoxyalkyl having from 2 to 5 carbon atoms, aralkyl having from 7 to 11 carbon atoms, cycloalkylalkyl having from 4 to 11 carbon atoms, alkylthioalkyl having from 2 to 5 carbon atoms, cycloalkyl having from 4 to 7 carbon atoms, and the acyl of an organic carboxylic acid having from 1 to 18 carbon atoms, as well as the process of preparing the same. These compounds are useful as intermediates in the preparation of 2-oxa steroids of the formula

which have an anabolic action coupled with an androgenic action.

REFERENCE TO PRIOR APPLICATIONS

This application is a continuation-in-part of our co-pending applications Ser. No. 603,094, filed Dec. 20, 1966, now U.S. Pat. No. 3,574,688, and Ser. No. 728,880, filed May 14, 1968, this latter application being a continuation-in-part of Ser. No. 603,457, filed Dec. 21, 1966, and now abandoned.

OBJECTS OF THE INVENTION

An object of the present invention is the obtention of a substituted des-A steroid of the formula

2

wherein R is an alkyl having from 1 to 6 carbon atoms, X is a member selected from the group consisting of hydrogen, alkyl having from 1 to 5 carbon atoms, alkenyl having from 3 to 5 carbon atoms, alkoxyalkyl having from 2 to 5 carbon atoms, aralkyl having from 7 to 11 carbon atoms, cycloalkylalkyl having from 4 to 11 carbon atoms, alkylthioalkyl having from 2 to 5 carbon atoms, cycloalkyl having from 4 to 7 carbon atoms, and the acyl of an organic carboxylic acid having from 1 to 18 carbon atoms.

Another object of the present invention is the development of a process for the production of the above substituted des-A steroids which comprises the steps of formylating the des-A-A⁹-gonene of the formula

15

20

wherein R is an alkyl having from 1 to 6 carbon atoms, X is a member selected from the group consisting of hydrogen, alkyl having from 1 to 5 carbon atoms, alkenyl having from 3 to 5 carbon atoms, alkoxyalkyl having from 2 to 5 carbon atoms, aralkyl having from 7 to 11 carbon atoms, cycloalkylalkyl having from 4 to 11 carbon atoms, alkylthioalkyl having from 2 to 5 carbon atoms, cycloalkyl having from 4 to 7 carbon atoms, and the acyl of an organic carboxylic acid having from 1 to 18 carbon atoms, by the action of a formylating agent, dehydrogenating the resulting 10-hydroxymethylene enone of the formula

25

30

wherein R and X have the above-assigned meanings, by the action of a dehydrogenating agent, reducing the resulting formyl dienone of the formula

35

40

45

wherein R and X have the above-assigned meanings, by the action of a metal hydride selected from the group consisting of an alkali metal borohydride and tri-t-butoxy-aluminum-lithium hydride, in the presence of a solvent media, and recovering said substituted des-A steroid.

50

55

60

65

A yet further object of the invention is the development of a process for the production of a 10-hydroxymethylene enone of the formula

wherein R is an alkyl having from 1 to 6 carbon atoms, X is a member selected from the group consisting of hydrogen, alkyl having from 1 to 5 carbon atoms, alkenyl having from 3 to 5 carbon atoms, alkoxyalkyl having from 2 to 5 carbon atoms, aralkyl having from 7 to 11 carbon atoms, cycloalkylalkyl having from 4 to 11 carbon atoms, alkylthioalkyl having from 2 to 5 carbon atoms, cycloalkyl having from 4 to 7 carbon atoms, and the acyl of an organic carboxylic acid having from 1 to 18 carbon atoms, which comprises the steps of condensing an enamine of the formula

wherein R and X have the above-assigned meanings, and R₂ and R₃ are selected from the group consisting of alkyl having from 1 to 8 carbon atoms, and, when taken together, alkylene having from 4 to 5 carbon atoms and alkylene-oxyalkylene having 4 carbon atoms, with a mixed formic-acetic acid anhydride, hydrolyzing the resulting iminium of the formula

wherein R, R₂, R₃ and X have the above-assigned meanings, by the action of an acid, and recovering said 10-hydroxy-methylene enone.

A still further object of the invention is the obtention of an intermediate steroid precursor selected from the group consisting of (1) a 10-hydroxymethylene enone of the formula

and (2) a 10-formyl-dienone of the formula

wherein R is an alkyl having from 1 to 6 carbon atoms, X is a member selected from the group consisting of hydrogen, alkyl having from 1 to 5 carbon atoms, alkenyl having from 3 to 5 carbon atoms, alkoxyalkyl having from 2 to 5 carbon atoms, aralkyl having from 7 to 11 carbon atoms, cycloalkylalkyl having from 4 to 11 carbon atoms, alkylthioalkyl having from 2 to 5 carbon atoms, cycloalkyl having from 4 to 7 carbon atoms, and the acyl of an organic carboxylic acid having from 1 to 18 carbon atoms and A is a member selected from the group consisting of oxygen and a ketal group.

These and other objects of the present invention will become more apparent as the description of the invention proceeds.

DESCRIPTION OF THE INVENTION

The invention relates to new cyclopentanopolyhydro-naphthalene derivatives, which for a better understanding will be designated in the following by the terms usually used in steroid chemistry, that is to say, their names are derived from those of the corresponding tetracyclic compounds by having them preceded with the prefix "des-A."

These new "Des-A" steroid derivatives of the invention are represented by the general Formula I

wherein R is an alkyl having from 1 to 6 carbon atoms, and X is selected from the group consisting of hydrogen, alkyl having from 1 to 5 carbon atoms, alkenyl having from 3 to 5 carbon atoms, alkoxyalkyl having from 2 to 5 carbon atoms, aralkyl having from 7 to 11 carbon atoms, cycloalkylalkyl having from 4 to 11 carbon atoms, alkylthioalkyl having from 2 to 5 carbon atoms, cycloalkyl having from 4 to 7 carbon atoms, and the acyl of an organic carboxylic acid having from 1 to 18 carbon atoms.

In the general Formula I the alkyl, R, is advantageously one of the following: methyl, ethyl, propyl, isopropyl, butyl or isobutyl.

The new compounds of the general Formula I are useful as intermediates in the synthesis of the 2-oxa steroids of the general formula

wherein R and X retain the previous significance. These 2-oxa steroids possess particularly an important anabolic action and an androgenic action.

The process for the preparation of these 2-oxa steroids consists in that a compound of the general Formula I is condensed with an alkyl haloacetate, preferably a lower alkyl haloacetate such as ethyl bromoacetate, in the presence of zinc, preferably at the reflux temperature of the solvent employed, and in that the condensation product is treated with an acid agent, preferably a strong mineral or organic acid such as hydrochloric acid or p-toluenesulfonic acid.

The reaction formula given below illustrates the process for the preparation of the said 2-oxa steroids.

R and X have the above-assigned meanings.

The process for the preparation of the compounds of the general Formula I, a further object of the invention, is characterized in that by the reaction of a formylation agent with a des-A- Δ^9 -gonene-5-one of the general Formula II

R and X retaining, here and in the following, the above-assigned meanings, the corresponding 10-hydroxymethylene enone of the general Formula III

is obtained which under the action of dehydrogenation agent leads to the formyl dienone of the general Formula IV

the aldehyde group of which is selectively reduced into an alcohol group with the aid of a mixed alkali metal

hydride selected from the group consisting of an alkali metal borohydride and tri-t-butoxy-aluminum-lithium hydride, and the desired hydroxymethyl dienone of the general Formula I

is obtained.

The formylation is preferably realized according to the method of Vilsmeier Haack (Ber. 60B, 119 [1927]). For example, the dimethylformamide-phosphorus oxychloride complex is used, but it is evident that other complexes of other substituted formamides, for example, N,N-disubstituted formamides such as N-methyl-N-phenylformamide or N-piperidino-N-methylformamide, with other inorganic chlorination agents, for example, phosgene, sulfuryl chloride or phosphorus pentachloride are also suitable.

The reaction is effected in an organic solvent, for example, methylene chloride, working at room temperature or in the neighborhood of room temperature.

The dehydrogenation of the 10-hydroxymethylene enone of the general Formula III is effected with the aid of a substituted p-quinone, preferably a halo or cyano substituted p-benzoquinone selected from the group consisting of halo-substituted p-benzoquinones, cyano-substituted p-benzoquinones and halo-cyano-substituted p-benzoquinones, such as 2,3-dichloro-5,6-dicyano-p-benzoquinone, 2,3-dibromo-5,6-dicyano-p-benzoquinone, 2,3,5,6-tetrachloro-p-benzoquinone, 2,3-dicyano-5-chloro-p-benzoquinone and 2,3-dicyano-p-benzoquinone. Advantageously, the work is carried out in dioxane.

The alkali metal borohydride utilized for the selective reduction of the aldehyde function of the dienic compound of the general Formula IV is preferably sodium or potassium borohydride. The reaction is conducted in a solvent such as aqueous dioxane, while slightly cooling and utilizing the theoretical amount of borohydride.

A variant of the process of the invention consists in that instead of the starting tricyclic ketone of the general Formula II, the corresponding enamine of the general Formula A

is utilized, wherein R and X retain the previous meaning, R₂ represents an alkyl radical containing from 1 to 8 carbon atoms, R₃ represents an alkyl radical containing from 1 to 8 carbon atoms, or R₂ and R₃ together, represent a chain selected from the group consisting of an alkylene chain containing from 4 to 5 carbon atoms, and an alkyleneoxyalkylene chain containing 4 carbon atoms. This enamine is condensed with mixed formic-acetic acid anhydride; then the resultant iminium of the general Formula VI

is subjected to an acid hydrolysis to obtain the corresponding 10-hydroxymethylene enone of the general Formula III

The synthesis is then proceeded with as described above.

Preferably, in the general Formula I, R can be methyl, ethyl and propyl; and X can be hydrogen, alkyl having from 1 to 5 carbon atoms such as methyl, ethyl, propyl, etc., alkenyl having from 3 to 5 carbon atoms, such as Δ^1 -propenyl, methylallyl, dimethylallyl, etc., cycloalkyl having from 4 to 7 carbon atoms, such as cyclopentyl or cyclohexyl, cycloalkylalkyl having from 4 to 11 carbon atoms, such as hexahydrobenzyl or substituted hexahydrobenzyl, alkoxyalkyl having from 2 to 5 carbon atoms, such as methoxymethyl, ethoxyethyl, etc., alkylthioalkyl having from 2 to 5 carbon atoms, such as methylthiomethyl and the like, arylalkyl, preferably phenylalkyl having from 7 to 11 carbon atoms, such as benzyl, and the acyl of an organic carboxylic acid having from 1 to 18 carbon atoms selected from the group consisting of alcanoic acids, such as acetic acid, propionic acid, lauric acid, etc., alkenoic acids such as oleic acid, etc., benzoic acid, hexahydrobenzoic acid, cycloalkylalkanoic acids, such as cyclopentyl-, cyclohexyl-, acetic or propionic acids, etc., phenylalkanoic acids such as phenylacetic acid, phenylpropionic acid etc., phenoxyalkanoic acids such as phenoxyacetic acid, heterocyclic carboxylic acids such as furan-2-carboxylic acid, 5-tertbutylfuran - 2 - carboxylic acids, etc., and β -keto-alkanoic acids such as acetylacetic acid, etc.

It is preferred to utilize the benzoate ester in the synthesis of the invention. However, the 17-ethers and the 17-alcohol can also be utilized. Among the 17-ethers are the 17 β -methoxy, the 17 β -ethoxy, the 17 β -allyloxy, the 17 β -methoxymethoxy, etc.

The starting products of the present process can be obtained, for example, according to the processes described in French Pat. No. 1,234,734, in Belgian Pat. No. 599,342 and in U.S. Pat. No. 3,168,530.

Another variant of the process of the invention consists in that instead of the starting tricyclic ketone of the general Formula II, the corresponding tricyclic ketone where X is the acyl radical of an organic carboxylic acid having from 1 to 18 carbon atoms or the corresponding enamine is utilized as the starting compound. This variant, following the above procedures results in the formyl dienone of the general Formula IV where X is acyl. The 10-formyl-des-A- $\Delta^9,11$ -gonadiene-5-one thus formed, of the Formula IV (X=acyl)

wherein R has the above-assigned meanings and acyl represents the acyl of an organic carboxylic acid having

from 1 to 18 carbon atoms, is reacted with a ketalizing agent. The resultant diketal of the Formula VII

wherein K is a ketal group, R and Acyl have the above-assigned means, is saponified by the action of an alkaline agent. The resultant 17 β -ol derivatives of the Formula VIII

wherein K and R have the above-assigned meanings, is etherified by the action of a halogenide of the formula

wherein Hal is a halogen atom other than fluorine, and X' is selected from the group consisting of alkyl having from 1 to 5 carbon atoms, alkenyl having from 3 to 5 carbon atoms, cycloalkyl having from 4 to 7 carbon atoms, alkoxyalkyl having from 2 to 5 carbon atoms, aralkyl having from 7 to 11 carbon atoms, cycloalkylalkyl having from 4 to 11 carbon atoms, and alkylthioalkyl having from 2 to 5 carbon atoms. The resultant 17-ether of the Formula IX

wherein R, K and X' have the above-assigned meanings, is subjected to an acid hydrolysis, such as an aqueous organic acid. The resultant 10-formyl-des-A-gonadiene of the Formula IV (where X=X')

wherein R and X' have the above-assigned meanings, is reduced by the action of a mixed alkali metal hydride, and the 10-hydroxymethyl derivative of Formula I, where X=X', is recovered.

The execution of the above variant of the process of the invention can preferably be effected in the following manner:

(a) The ketalizing agent is selected from the group consisting of the lower cyclic ketals, preferably the 2-dilower alkyl-dioxolanes, for example, 2-methyl-2-ethyl-dioxolane, and the lower alkanediols, for example, ethylene-glycol. The reaction is conducted in the presence of an acid catalyst, preferably a strong organic catalyst, such as p-toluenesulfonic acid.

(b) The alkaline agent used in the saponification step is an alkali metal hydroxide, such as sodium or potassium

hydroxide, in the presence of a lower alkanol such as methanol or ethanol.

(c) The etherification step is carried out in the presence of a basic agent, for example, a metal hydride such as sodium hydride, in a polar solvent such as tetrahydrofuran, dimethylformamide or dimethylsulfoxide.

(d) The mixed hydride is selected from the group consisting of an alkali metal borohydride, such as sodium borohydride, and an alkali metal hydridotrialkoxoaluminate, such as lithium hydridotriisobutoxidoaluminate. The reaction is preferably performed in aqueous dioxane in the first case, and in tetrahydrofuran in the second case.

The following examples will serve for better comprehension of the invention. However, it is to be understood that they do not limit the invention in any manner.

EXAMPLE I

Preparation of 10-hydroxymethyl-13 β -methyl-17 β -benzoyloxy-des-A- $\Delta^{9,11}$ -gonadiene - 5 - one (or 10-hydroxymethyl-17 β -benzoyloxy-des-A- $\Delta^{9,11}$ -estradiene-5-one)

Step A: Preparation of 10 - hydroxymethylene-13 β -methyl-17 β -benzoyloxy-des-A- $\Delta^{9(11)}$ -gonene - 5 - one (or 10-hydroxymethylene - 17 β - benzoyloxy-des-A- $\Delta^{9(11)}$ -estrone-5-one).—Dropwise and while agitating at room temperature, 15 cc. of anhydrous phosphorus oxychloride were introduced into 6.2 cc. of anhydrous dimethylformamide, and the solution was allowed to stand for 2 hours.

At the same time, 3 gm. of 13 β -methyl-17 β -benzoyloxy-des-A- Δ^9 -gonene-5-one (described in French Pat. No. 1,234,734) were placed in suspension in 3 cc. of methyl-ene chloride.

The temperature of the suspension was lowered to 16° C. Then 6 cc. of the phosphorus oxychloride-dimethyl-formamide complex, prepared as previously described, were introduced therein under vigorous agitation, without exceeding a temperature of 20° C., and the reaction mixture was agitated for 10 minutes more.

Thereafter, the reaction mixture was poured into iced water, agitated for several minutes, extracted first with benzene, then with ether. The resultant extracts were combined, washed with water and decanted. 2 cc. of formic acid were added to the washed extract and the agitation was continued under an atmosphere of nitrogen for about 1½ hours. Thereafter, the solution obtained was washed first with an aqueous tartaric acid solution, then with water, with a 5% potassium carbonate solution in water and lastly with water.

Next, the desired product was isolated by washing the organic extract with an iced aqueous solution of 0.28 N potassium hydroxide. After acidification of the aqueous solution of the potassium salt with sulfuric acid to a pH of 3 to 4, the solution was extracted with ether, which was dried and the solvent was evaporated. A residue was obtained which crystallized on addition of ethanol.

After recrystallization from isopropanol containing 10% of water, pure 10 - hydroxymethylene-13 β -methyl-17 β -benzoyloxy-des-A- $\Delta^{9(11)}$ -gonene-5-one, having a melting point of 129° to 130° C., was obtained with a yield of 34%.

The product was insoluble in water and in dilute aqueous acids, slightly soluble in cold alcohols and isopropyl ether, and soluble in dilute aqueous alkalis, hot alcohols, ether, chloroform, methylene chloride, toluene and ethyl acetate. It gave an intense blue reaction with ferric chloride.

Analysis.—Calculated for C₂₂H₂₄O₄ (molecular weight =352.41) (percent): C, 74.97; H, 6.86; O, 18.16. Found (percent): C, 75.0; H, 7.0; O, 18.1.

This compound is not described in the literature.

Step B: Preparation of 10-formyl-13 β -methyl-17 β -benzoyloxy-des-A- $\Delta^{9,11}$ -gonadiene-5-one.—At room temperature, 10.6 gm. of 10-hydroxymethylene-13 β -methyl-17 β -benzoyloxy-des-A- $\Delta^{9(11)}$ -gonene-5-one were dissolved in 106 cc. of anhydrous dioxane. The solution was slightly cooled, and, in the space of a few minutes, 7.15 gm. of

2,3 - dichloro - 4,6-dicyano-p-benzoquinone were added thereto. The reaction mixture was agitated for 1 hour under an atmosphere of nitrogen.

Next, the reaction mixture was filtered and the insoluble portion was washed with methylene chloride. The filtrate was poured into water and extracted with ether.

The extracts obtained were washed successively first with a saturated aqueous solution of sodium bicarbonate, then with a N sodium hydroxide solution, with water and finally salt water. The extract was then dried, distilled under vacuum, and the residue was crystallized by trituration in ether.

The crystals were vacuum filtered, and 4.14 gm. of 10-formyl - 13 β - methyl-17 β -benzoyloxy-des-A- $\Delta^{9,11}$ -gonadiene-5-one, that is 39% of the theory, were obtained. The product after recrystallization from ethanol had a melting point of 137° to 138° C., and a specific rotation [α]_D = -62.3° (c. = 0.94% in chloroform).

Infrared spectra (chloroform):

CHO at 1690 cm.⁻¹ and CH at 2750 cm.⁻¹
C=O at 1665 cm.⁻¹
C=C at 1593 cm.⁻¹ and 1543 cm.⁻¹
Benzene at 1715 cm.⁻¹ and 1279 cm.⁻¹

Ultraviolet spectra:

(1) Dioxane—
 λ_{max} at 230 m μ , ϵ = 19,000
and 303-304 m μ , ϵ = 21,000
(2) Ethanol and N/10 sodium hydroxide—
 λ_{max} at 231 m μ , ϵ = 21,000
and 259 m μ , ϵ = 14,000
and 333 m μ , ϵ = 7,900.

Analysis.—Calculated for C₂₂H₂₂O₄ (molecular weight =350.40) (percent): C, 75.40; H, 6.33. Found (percent): C, 75.7; H, 6.5.

The product was slightly soluble in alcohol and ether, and soluble in chloroform.

This compound is not described in the literature.

Step C: Preparation of 10-hydroxymethyl-13 β -methyl-17 β -benzoyloxy-des-A- $\Delta^{9,11}$ -gonadiene-5-one (or 10-hydroxymethyl - 17 β - benzoyloxy-des-A- $\Delta^{9,11}$ -estradiene-5-one).—At room temperature, 4.63 gm. of 10-formyl-13 β -methyl-17 β -benzoyloxy-des-A- $\Delta^{9,11}$ -gonadiene-5-one were dissolved in a mixture of 46 cc. of anhydrous dioxane and 4.6 cc. of water. The mixture was cooled to about 5° C.; then slowly, while agitating under an atmosphere of nitrogen, 0.141 gm. of sodium borohydride were introduced therein. The agitation was maintained for ½ hour. Then the reaction mixture was poured into water and extracted with methylene chloride.

The extracts obtained were washed first with water, then with salt water, dried and distilled to dryness under vacuum. The residue was dissolved in the minimum of a mixture of benzene and ethyl acetate (2:3) and subjected to chromatography through silica gel with the same mixture of solvents.

In this way, a crystallized product was obtained which, after recrystallization from ethyl acetate admixed with ether, furnished 2.6 gm. of 10-hydroxymethyl-13 β -methyl-17 β -benzoyloxy - des - A- $\Delta^{9,11}$ -gonadiene-5-one, that is a yield of 56%, with a melting point of 134° to 135° C. and a specific rotation [α]_D = -69.2° (c. = 0.9% in chloroform).

The product was insoluble in water, slightly soluble in ether, and soluble in alcohol and chloroform.

Infrared spectra (chloroform):

C=O and C=C at 1645 cm.⁻¹ and 1605 cm.⁻¹
Associated OH between 3560 and 3400 cm.⁻¹

Ultraviolet spectra (in ethanol):

λ_{max} . 230 m μ , ϵ = 15,050
 λ_{max} . 285 m μ , ϵ = 25,500

Analysis.—Calculated for C₂₂H₂₄O₄ (molecular weight =352.41) (percent): C, 74.97; H, 6.86. Found (percent): C, 74.8; H, 6.8.

11

This compound is not described in the literature.

The dehydrogenation step of Example I may be effected also in the following way:

Step B': Preparation of 10 - formyl - 13 β - methyl-17 β -benzoyloxy-des-A- $\Delta^{9,11}$ -gonadiene-5-one.—At room temperature, under stirring, 1 gm. of 10-hydroxymethylene-13 β - methyl - 17 β -benzoyloxy-des-A- $\Delta^{9,11}$ -gonene-5-one, obtained in the step A of Example I, was poured, in a suspension made of:

Tetrachloro-2,3,5,6-benzoquinone, gm. 1
Dioxane, cc. 8

The reaction mixture was kept under stirring for two minutes, then diluted with 30 cc. of an aqueous solution of sodium bicarbonate and sodium hydrosulfite.

The thus formed suspension was transferred into a decantation funnel, diluted again with 50 cc. of the said solution of sodium bicarbonate and extracted three times with ethylether.

The organic phases were separated, washed twice with 25 cc. of a 0.5 N solution of soda, with water and then dried and evaporated to dryness.

The crystalline residue was dried under vacuum. The 10 - formyl - 13 β - methyl-17 β -benzoyloxy-des-A- $\Delta^{9,11}$ -gonadiene-5-one was obtained with a yield of 0.895 gm. (90% of the theory).

This compound was purified by triturating with ethyl-ether. The pure sample for analysis melted at 135° then 138°.

It did not depress the melting point of the compound obtained at the step B of this example.

EXAMPLE II

Preparation of 10 - hydroxymethylene - 13 β - methyl-17 β -benzoyloxy - des-A- $\Delta^{9,11}$ -gonene-5-one (or 10-hydroxymethylene - 17 β - benzoyloxy - des-A- $\Delta^{9,11}$ -estrene-5-one) starting with the enamine of 13 β -methyl-17 β -benzoyloxy-des-A- Δ^9 -gonene-5-one

1 gm. of 5-pyrrolidyl-13 β -methyl-17 β -benzoyloxy-des-A- $\Delta^{5(10),9,11}$ -gonadiene, described in French Pat. No. 1,271,997 was dissolved in 5 cc. of anhydrous dioxane. The solution was cooled to a temperature of 10° C. 0.37 cc. of triethylamine were added and then 0.9 cc. of mixed formic acetic anhydride (J.A.C.S., 61, 3355 [1939]) were introduced dropwise therein.

Next, the reaction mixture was agitated for 1/2 hour at a temperature of about 10° C. and under an atmosphere of nitrogen. Then 2 cc. of water were added and the agitation was maintained for 2 hours altogether. Thereafter, it was poured into water and extracted with ether. The extracts were washed first with water, then with a saturated aqueous solution of sodium bicarbonate and lastly with an iced solution of N/10 sodium hydroxide.

The washed extract was acidified with hydrochloric acid and extracted with ether. The extracts were washed as described in the preceding but with a final washing with water, dried, filtered and evaporated to dryness. The residue was recrystallized from ethanol, thus obtaining 0.17 gm. of 10-hydroxymethylene-13 β -methyl-17 β -benzoyloxy-des-A- $\Delta^{9,11}$ -gonene-5-one, having a melting point of 129° to 130° C., identical to the compound obtained in step A of Example I.

In the same manner, starting with the des-A- Δ^9 -gonene-5-ones of the general Formula II or with their enamines, but having in the 13 position an alkyl other than methyl, such as ethyl, propyl, isopropyl, butyl, or isobutyl, the corresponding hydroxymethyl-dienones of the general Formula I were obtained.

EXAMPLE III

Preparation of 10-hydroxymethyl-13 β -ethyl-17 β -benzoyloxy-des-A- $\Delta^{9,11}$ -gonadiene-5-one

Step A: Preparation of 10-hydroxymethylene-13 β -ethyl - 17 β -benzoyloxy-des-A- $\Delta^{9,11}$ -gonene-5-one.—At room temperature, under agitation and an atmosphere of

12

nitrogen, 27.23 gm. of 5-pyrrolidino-13 β -ethyl-17 β -benzoyloxy-des-A- $\Delta^{5(10),9,11}$ -gonadiene (obtained according to the process described in U.S. Pat. No. 3,168,530) were dissolved in 272 cc. of dioxane and 136 cc. of tetrahydrofuran. Then, 20 cc. of triethylamine and, while maintaining the temperature between 0° C. and +5° C., 50 cc. of formic-acetic acid anhydride (obtained by the action of sodium formate on the acetyl chloride) were added thereto. Next, the mixture was agitated for 3 hours and 30 minutes. Then, 110 cc. of water were added and the reaction mixture was allowed to stand overnight at room temperature. Thereafter the reaction mixture was poured into a water-ice mixture. The precipitate was extracted with ether. The ethereal phase were separated and washed with water, then extracted with N/2 sodium hydroxide-ice mixture. The alkaline phase were acidified with hydrochloric acid to a pH of 1, and extracted with ether. The ethereal phases were washed with water, dried and distilled to dryness. The residue obtained was purified by dissolution in hot ethanol, which was then allowed to return to room temperature. Next, the mixture was iced for 30 minutes and vacuum filtered. The precipitate was washed first with ethanol, then with petroleum ether and finally dried. 14.72 gm. of 10-hydroxymethylene-13 β -ethyl-17 β -benzoyloxy-des-A- $\Delta^{9,11}$ -gonene-5-one were obtained in the form of clear, yellow crystals, soluble in acetone, chloroform and methanol, and insoluble in water. The product had a melting point of 118° C. and a specific rotation $[\alpha]_D^{20} = +58^\circ \pm 2^\circ$ (c.=0.5% in chloroform).

Analysis.—Calculated for $C_{23}H_{26}O_4$ (molecular weight=366.44) (percent): C, 75.38; H, 7.15. Found (percent): C, 75.1; H, 6.9.

This compound is not described in the literature.

Step B: Preparation of 10-formyl-13 β -ethyl-17 β -benzoyloxy-des-A- $\Delta^{9,11}$ -gonadiene-5-one.—At room temperature, under agitation and an atmosphere of nitrogen, 14.72 gm. of 10 - hydroxymethylene - 13 β - ethyl - 17 β -benzoyloxy-des-A- $\Delta^{9,11}$ -gonene-5-one were dissolved in a mixture of 75 cc. of dioxane and 75 cc. of ether. A solution of 10.5 gm. of dicyanodichlorobenzoquinone in 75 cc. of dioxane was added while maintaining the interior temperature between 8° C. and 10° C. Then, the mixture was agitated over a period of 45 minutes at room temperature. Next, the reaction mixture was poured into an iced solution of sodium bicarbonate and sodium bisulfite and extracted with ether. The ethereal phases were washed first with a mixture of 0.1 N sodium hydroxide and ice, then with water and finally distilled to dryness. 7.47 gm. of raw product were thus recovered, which was purified by chromatography through a column of alumina and elution with methylene chloride. In this manner, after evaporation of the solvent, 5.33 gm. of 10-formyl-13 β - ethyl - 17 β -benzoyloxy-des-A- $\Delta^{9,11}$ -gonadiene-5-one were obtained, which product was used as such in the next step.

This compound is not described in the literature.

Step C: Preparation of 10-hydroxymethyl-13 β -ethyl-17 β -benzoyloxy-des-A- $\Delta^{9,11}$ -gonadiene-5-one.—At room temperature, under agitation and an atmosphere of nitrogen, 5.42 gm. of 10-formyl-13 β -ethyl-17 β -benzoyloxy-des-A- $\Delta^{9,11}$ -gonadiene-5-one were dissolved in 54 cc. of dioxane. The temperature was brought to +5° C., and 180 mg. of sodium borohydride were added to the solution. The reaction mixture was kept under agitation for one hour, then poured into a water-ice mixture. The mixture was then extracted with methylene chloride. Next, the methylene chloride phases were washed with water, dried and distilled to dryness. The resultant residue was subjected to chromatography through alumina and eluted with methylene chloride. After the evaporation of the solvent, 3.15 gm. of 10-hydroxymethyl-13 β -ethyl-17 β -benzoyloxy-des-A- $\Delta^{9,11}$ -gonadiene-5-one were obtained.

For analysis, the product was recrystallized from ether and petroleum ether. This compound occurred in the

form of yellowish crystals, soluble in acetone, chloroform and alcohol, and insoluble in water. It had a melting point of 90° C. and a specific rotation $[\alpha]_D^{20} = -74^\circ \pm 2^\circ$ (c. = 0.2% in chloroform).

Analysis. — Calculated for $C_{23}H_{26}O_4$ (molecular weight = 366.44) (percent): C, 75.38; H, 7.15. Found (percent): C, 75.2; H, 7.3.

This compound is not described in the literature.

EXAMPLE IV

Preparation of 10-hydroxymethyl-13 β -methyl-17 β -benzyloxy-des-A- $\Delta^{9,11}$ -gonadiene-one

Step A: Preparation of 5-ethylenedioxy-10-(ethylenedioxy)-methyl-13 β -methyl-17 β -benzyloxy-des-A- $\Delta^{9,11}$ -gonadiene. — 5 gm. of 10-formyl-13 β -methyl-17 β -benzyloxy-des-A- $\Delta^{9,11}$ -gonadiene-5-one (as described in Example I, step B) and 0.15 gm. of paratoluene sulfonic acid were introduced into 150 cc. of chloroform and 15 cc. of ethylene glycol under an atmosphere of nitrogen. The mixture was heated to reflux under agitation for 30 hours. The distillate was dried over a dehydrating agent before being recycled. Then 0.05 gm. of paratoluene sulfonic acid was added and the mixture was again heated to reflux under the previously described conditions for 15 hours. The reaction mixture was cooled, made alkaline by addition of triethylamine and diluted with water. The aqueous phase was extracted with methylene chloride, and the extracts were combined with the organic phase. The organic solution thus obtained was washed with water, dried and evaporated to dryness under reduced pressure. The residue was chromatographed over silica gel and eluted with an ethyl acetate-benzene mixture (1:9). 2.4 gm. of raw mono-ketal (M.P. 192° C.) were first eluted; then 1.7 gm. of raw diketal (M.P. 175° C.) was collected.

After recrystallization of the raw diketal from ethanol, 1.27 gm. of pure 5 - ethylenedioxy-10-(ethylenedioxy)-methyl-13 β -methyl-17 β -benzyloxy-des-A- $\Delta^{9,11}$ -gonadiene, having a melting point of 176° C., was obtained.

Analysis. — Calculated for $C_{26}H_{30}O_6$ (molecular weight = 438.5) (percent): C, 71.2; H, 6.9. Found (percent): C, 71.2; H, 7.2.

Ultraviolet spectrum (in ethanol): λ_{max} . at 239-240 m μ , ϵ =32,850.

Step B: Preparation of 5 - ethylenedioxy-10-(ethylenedioxy) methyl - des - A - $\Delta^{9,11}$ - gonadiene - 17 β - ol. — A mixture of 4.77 gm. of 5 - ethylenedioxy-10-(ethylenedioxy) methyl - 13 β -methyl-17 β -benzyloxy-des-A- $\Delta^{9,11}$ -gonadiene and 48 cc. of a N potassium hydroxide solution in 95% ethanol was heated to reflux for 30 minutes and then 250 cc. of water were added. The reaction mixture was extracted with methylene chloride. The organic phases were washed with water, dried over sodium sulfate, filtered and evaporated to dryness under vacuum to yield 3.8 gm. of raw 17 β -hydroxy derivative. 200 mg. of raw product were pasted in isopropyl ether at reflux temperature. After cooling, the precipitate was filtered, washed with isopropyl ether and dried, whereby 175 mg. (92% yield) of product were obtained. This product was purified by recrystallization from ethyl acetate, thus affording 105 mg. of 5 - ethylenedioxy-10-(ethylenedioxy) methyl-13 β -methyl-des-A- $\Delta^{9,11}$ -gonadiene-17 β -ol. The product occurred in the form of colorless crystals, soluble in ethanol and methylene chloride, insoluble in water, and melting at 183° C.

Analysis. — Calculated for $C_{19}H_{26}O_5$ (molecular weight = 334.40) (percent): C, 68.24; H, 7.84. Found (percent): C, 68.4; H, 7.5.

Ultraviolet spectrum (in ethanol): λ_{max} . at 247 m μ , ϵ =23,200.

Step C: Preparation of 5-ethylenedioxy-10-(ethylenedioxy) methyl - 13 β - methyl-17 β -benzyloxy-des-A- $\Delta^{9,11}$ -gonadiene. — 8.5 gm. of 5 - ethylenedioxy-10-(ethylenedioxy) methyl - 13 β -methyl-17 β -hydroxy-des-A- $\Delta^{9,11}$ -gonadiene were dissolved in 180 cc. of tetrahydrofuran. Then 3.2 gm. of a suspension of 50% sodium hydride in par-

affin oil were added to the solution, and the whole was heated to reflux for 30 minutes. Then 12.5 cc. of benzyl bromide were added, and the heating at reflux was continued for a period of 90 minutes. The reaction mixture was cooled to room temperature and poured into a mixture of water, ice and aqueous sodium hydroxide solution. The aqueous phase was extracted with methylene chloride, the extracts were combined, washed with water, dried and concentrated to dryness. The residue was triturated with petroleum ether (B.P. 65-75° C.) to afford 7.65 gm. of 5 - ethylenedioxy-10-(ethylenedioxy) methyl-13 β - methyl-17 β -benzyloxy-des-A- $\Delta^{9,11}$ -gonadiene melting at 160° C.

The analytical sample, M.P. 163 C., was obtained by recrystallization from methanol containing 2 parts per thousand of triethylamine.

Analysis. — Calculated for $C_{26}H_{32}O_5$ (molecular weight = 424.52) (percent): C, 73.57; H, 7.59. Found percent: C, 73.5; H, 7.8.

Ultraviolet spectrum (in ethanol): λ_{max} . at 246 m μ , ϵ =23,600.

Step D.: Preparation of 10-formyl-13 β -methyl-17 β -benzyloxy-des-A- $\Delta^{9,11}$ -gonadiene - 5 - one. — Under an atmospheric of nitrogen, 7.98 gm. of 5-ethylenedioxy-10-(ethylenedioxy) methyl-13 β -methyl-17 β -benzyloxy-des-A- $\Delta^{9,11}$ -gonadiene were dissolved in 60 cc. of acetic acid, then 20 cc. of water were added and the mixture was stirred at room temperature for 1 hour. Then a water-ice mixture was added, and the precipitate thus formed was vacuum-filtered, washed with water and dried to yield 6.05 gm. of raw 10-formyl-13 β -methyl-17 β -benzyloxy-des-A- $\Delta^{9,11}$ -gonadiene-5-one, having a melting point of 120° C., which product was used as such in the next step.

Step E: 10-hydroxymethyl-13 β -methyl-17 β -benzyloxy-des-A- $\Delta^{9,11}$ -gonadiene-5-one. — Under an atmosphere of nitrogen, 6.84 gm. of raw 10-formyl-13 β -methyl-17 β -benzyloxy-des-A- $\Delta^{9,11}$ -gonadienes-5-one were dissolved in 70 cc. of dioxane. The mixture was cooled to +10° C., and a cold solution of 0.200 gm. of sodium borohydride in 7 cc. of water was added dropwise. The reaction mixture was stirred for 20 minutes, and 0.020 gm. of sodium borohydride was then added. After an additional stirring at +10° C. for 10 minutes, the mixture was poured into water. The aqueous layer was extracted with methylene chloride, the combined extracts were washed, first with water, then with a N/10 sodium hydroxide aqueous solution and finally with water. The extracts were dried and concentrated to dryness. The residue was purified by chromatography through silica gel to afford 4.14 gm. of 10-hydroxymethyl - 13 β - methyl - 17 β - benzyloxy-des-A- $\Delta^{9,11}$ -gonadiene-5-one, having a melting point of 115° C.

EXAMPLE V

Preparation of 10-hydroxymethyl-13 β -methyl-17 β -hexahydrobenzyloxy-des-A- $\Delta^{9,11}$ -gonadiene-5-one

Step A: 5 - ethylenedioxy - 10-(ethylenedioxy)-methyl-13 β - methyl - 17 β - hexahydrobenzyloxy - des-A- $\Delta^{9,11}$ -gonadiene. — By following the procedure of step C of Example IV, 5-ethylenedioxy-10-(ethylenedioxy)-methyl-13 β -methyl-des-A- $\Delta^{9,11}$ -gonadiene-17 β -ol was reacted in a dimethyl sulfoxide tetrahydrofuran mixture with hexahydrobenzyl bromide to give 5-ethylenedioxy-10-(ethylenedioxy) - methyl-13 β -methyl-17 β -hexahydrobenzyloxy-des-A- $\Delta^{9,11}$ -gonadiene, having a melting point of 180° C. and a specific rotation $[\alpha]_D^{20} = -122^\circ$ (c. = 0.5% in chloroform).

Ultraviolet spectrum (in ethanol): λ_{max} . at 247 m μ , ϵ =23,700.

This compound is not described in the literature.

Step B: 10 - formyl - 13 β -methyl-17 β -hexahydrobenzyloxy - des - A - $\Delta^{9,11}$ -gonadiene-5-one. — Following the procedure of step D of Example IV, 5-ethylenedioxy-10-(ethylenedioxy) - methyl - 13 β -methyl-17 β -hexahydrobenzyloxy-des-A- $\Delta^{9,11}$ -gonadiene was converted by acetic acid hydrolysis, into 10-formyl-13 β -methyl-17 β -hexahydrobenzyl-

15

oxy-des-A- $\Delta^{9,11}$ -gonadiene-5-one, having a melting point of 107° C. and a specific rotation $[\alpha]_{D}^{20} = -115^{\circ}$ (c.=0.6% in chloroform). This material was used as such in the next step.

Step C: 10-hydroxymethyl-13 β -methyl-17 β -hexahydrobenzyloxy-des-A- $\Delta^{9,11}$ -gonadiene-5-one.—By following the procedure of step E of Example IV, the material obtained under step B above was converted by treatment with sodium borohydride into raw 10-hydroxymethyl-13 β -methyl-17 β -hexahydrobenzyloxy-des-A- $\Delta^{9,11}$ -gonadiene-5-one.

EXAMPLE VI

Preparation of 10-hydroxymethyl-13 β -methyl-17 β -(2'-methyl)-allyloxy-des-A- $\Delta^{9,11}$ -gonadiene-5-one

Step A: 5 - ethylenedioxy - 10 - (ethylenedioxy) - methyl-13 β - methyl - 17 β - benzyloxy-des-A- $\Delta^{9,11}$ -gonadiene.—This compound was obtained as described in Example IV, step A.

Step B: Preparation of 5 - ethylenedioxy-10-(ethylene-dioxy) - methyl - 13 β - methyl-des-A- $\Delta^{9,11}$ -gonadine-17 β -ol.—This compound was obtained as described in Example IV, step B.

Step C: 5 - ethylenedioxy-10-(ethylenedioxy) methyl-13 β - methyl-17 β -(2'-methyl) allyloxy-des-A- $\Delta^{9,11}$ -gonadiene.—2.4 gm. of a suspension of 50% sodium hydride in mineral oil and 24 cc. of tetrahydrofuran were stirred at room temperature under nitrogen for a period of 5 minutes. A solution of 4.09 gm. of 5-ethylenedioxy-10-(ethylenedioxy) methyl-13 β -methyl-des-A- $\Delta^{9,11}$ -gonadine-17 β -ol in 50 cc. of tetrahydrofuran was added thereto and the whole was heated to reflux for 30 minutes.

A solution of 9 gm. of β -methylallyl chloride in 36 cc. of tetrahydrofuran was then added and the whole was added to reflux for 18 hours. After cooling, 300 cc. of water were added, and the reaction mixture was extracted with methylene chloride. The extracts were washed with water, dried over sodium sulfate, filtered, and evaporated to dryness under vacuum, thus yielding 5.55 gm. of raw 17 β -methylallyl derivative which was recrystallized from isopropyl ether (yield 2.44 gm.).

Another crystallization from isopropyl ether afforded an analytical sample which occurred in the form of colorless needles, soluble in ethanol and methylene chloride and insoluble in water. It melted at 137° C. and had a specific rotation $[\alpha]_{D}^{20} = -160^{\circ} \pm$ (c.=0.2% in chloroform).

Analysis.—Calculated for $C_{23}H_{32}O_5$ (molecular weight =388.49) (percent): C, 71.10; H, 8.30. Found (percent): C, 71.1; H, 8.3.

Ultraviolet spectrum (in ethanol): $\lambda_{\text{max.}}$ at 246 to 247 $m\mu$, $\epsilon=23,100$.

This compound is not described in the literature.

Step D. Preparation of 10-formyl-13 β -methyl-17 β -(2'-methyl) allyloxy-des-A- $\Delta^{9,11}$ -gonadiene-5-one.—A solution of 2.2 gm. of 5-ethylenedioxy-10-(ethylenedioxy) methyl-13 β -methyl-17 β -(2'-methyl) allyloxy-des-A- $\Delta^{9,11}$ -gonadiene in 16.5 cc. of acetic acid and 5.5 cc. of water was stirred under nitrogen for 1 hour at room temperature and then poured into 400 cc. of saturated aqueous solution of sodium bicarbonate. The mixture was extracted with methylene chloride, and the extracts were washed with water until the wash waters were neutral, dried over sodium sulfate, filtered and evaporated to dryness. There was obtained 1.73 gm. of 10-formyl-13 β -methyl-17 β -(2'-methyl) allyloxy-des-A- $\Delta^{9,11}$ -gonadiene-5-one which occurred in the form of yellow prisms, soluble in acetic acid and methylene chloride, insoluble in water. The material melted at about 58° C.

Ultraviolet spectrum (in ethanol): $\lambda_{\text{max.}}$ at 233 $m\mu$, $\epsilon=6,450$; $\lambda_{\text{max.}}$ at $m\mu$, $\epsilon=19,500$.

This compound is not described in the literature.

Step E: Preparation of 10-hydroxymethyl-13 β -methyl-17 β -(2'-methyl)-allyloxy-des-A- $\Delta^{9,11}$ -gonadiene-5-one.—2.92 gm. of 10-formyl-13 β -methyl-17 β -(2'-methyl) allyloxy-des-A- $\Delta^{9,11}$ -gonadiene-5-one were introduced into 30

16

cc. of dioxane and 3 cc. of water. After cooling to +8° C., 100 mg. of sodium borohydride were added, the mixture was stirred at +10° C. for a period of 30 minutes, poured into a saturated aqueous solution of sodium chloride and extracted with methylene chloride. The organic phases were washed with water, dried over sodium sulfate, filtered and evaporated to dryness, thus yielding 2.8 gm. of raw 10-hydroxymethyl derivative which was purified by chromatography through silica gel followed by elution with an ethyl acetate-benzene mixture (5-5). In this way, 1.28 gm. of 10-hydroxymethyl-13 β -methyl-17 β -(2'-methyl) allyloxy-des-A- $\Delta^{9,11}$ -gonadiene-5-one was obtained in the form of colorless crystals, soluble in methylene chloride, benzene and ethyl acetate, insoluble in water, and melting at 102° C.

Ultraviolet spectrum (in ethanol): $\lambda_{\text{max.}}$ at 288 to 289 $m\mu$, $\epsilon=23,150$.

This compound is not described in the literature.

EXAMPLE VII

Preparation of 10-hydroxymethyl-13 β -methyl-17 β -(3'-methyl-2'-butenyl)-allyloxy-des-A- $\Delta^{9,11}$ -gonadiene-5-one

Step A: Preparation of 5-ethylenedioxy-10-(ethylenedioxy) methyl-13 β -methyl-17 β -(3'-methyl-2'-butenyl)-allyloxy-des-A- $\Delta^{9,11}$ -gonadiene.—3.4 g. of raw 5-ethylenedioxy-10-(ethylenedioxy) methyl-13 β -methyl-des-A- $\Delta^{9,11}$ -gonadiene-17 β -ol (obtained in step B of Example IV) were introduced into 35 cc. of tetrahydrofuran under an atmosphere of nitrogen and then 1 gm. of a suspension of 50% sodium hydride in paraffin oil was added. The mixture was heated to reflux for 30 minutes. Then 6 gm. of 1-bromo-3-methyl-2-butene were introduced therein and the heating at reflux was continued for 2 hours. The reaction mixture was then cooled and subjected to hydrolysis by adding an aqueous solution of sodium bicarbonate. The aqueous layer was extracted with methylene chloride. The combined extracts were washed with water, dried and concentrated to dryness. The residue was taken up with diethyl ether containing 0.5% of triethylamine. The precipitate was vacuum-filtered, and dried, thus affording 3.61 gm. of raw material which was recrystallized from methanol containing 1 part per thousand of triethylamine. Thus, 1.33 gm. of 5 - ethylenedioxy-10-(ethylenedioxy) methyl-13 β -methyl-17 β -(3'-methyl - 2' - butenyl)-allyloxy-des-A- $\Delta^{9,11}$ -gonadiene was obtained, which had a melting point of 144° C. and a specific rotation $[\alpha]_{D}^{20} = -134^{\circ}$ (c.=0.5% in chloroform).

Analysis.—Calculated for $C_{24}H_{34}O_5$ (molecular weight=402.51) (percent): C, 71.61; H, 8.51. Found (percent): C, 71.8; H, 8.5.

Ultraviolet spectrum (in ethanol): $\lambda_{\text{max.}}$ at 246 $m\mu$, $\epsilon=23,500$.

This compound is not described in the literature.

Step B: Preparation of 10-formyl-13 β -methyl-17 β -(3'-methyl-2'-butenyl)-des-A- $\Delta^{9,11}$ -gonadiene - 5 - one.—Under an atmosphere of nitrogen, 3.4 gm. of raw 5-ethylenedioxy-10-(ethylenedioxy) methyl-13 β -methyl-17 β -(3'-methyl - 2' - butenyl)-allyloxy-des-A- $\Delta^{9,11}$ -gonadiene were stirred until dissolved, in 26.4 cc. of acetic acid. Next, 8 cc. of water were added and stirring was continued for 1 hour at room temperature. The reaction mixture was poured into 400 cc. of a saturated aqueous solution of sodium bicarbonate, and the aqueous phase was extracted with methylene chloride. The extracts were washed with water, dried and evaporated to dryness, thus yielding 2.9 gm. of 10 - formyl-13 β -methyl-17 β -(3'-methyl-2'-butenyl)-allyloxy-des-A- $\Delta^{9,11}$ -gonadiene-5-one. This product was used as such for the next step.

Ultraviolet spectrum (in ethanol):

70 $\lambda_{\text{max.}}$ at 230 $m\mu$ $E_{1\text{cm.}}^{1\%} = 195$

$\lambda_{\text{max.}}$ at 308 $m\mu$ $E_{1\text{cm.}}^{1\%} = 505$ or $\epsilon=15,860$.

This compound is not described in the literature.

Step C: Preparation of 10-hydroxymethyl-13 β -methyl-17 β -(3'-methyl - 2' - butenyl)-allyloxy-des-A- $\Delta^{9,11}$ -gonadiene-

5-one.—Under an atmosphere of nitrogen, 2.71 gm. of 10-formyl-13 β -methyl-17 β -(3'-methyl - 2' - butenyoxy)-des-A- $\Delta^9,11$ -gonadiene-5-one were introduced into 30 cc. of tetrahydrofuran; the mixture was cooled to +5° C. and 2.95 gm. of lithium hydridotri isobutoxyaluminate were added thereto. The whole was stirred for 30 minutes at +5° C., then diluted with water and brought to a pH of 3.5 by addition of acetic acid. The aqueous layer was extracted with diethyl ether. The extracts were first washed with an aqueous solution of sodium chloride, then with an aqueous solution of sodium bicarbonate and again with the solution of sodium chloride. The extracts were then dried and evaporated to dryness. The residue was chromatographed over silica gel to afford 1.35 g. of 10-hydroxymethyl-13 β -methyl-17 β -(3'-methyl - 2' - butenyoxy)-des-A- $\Delta^9,11$ -gonadiene-5-one. 15

Ultraviolet spectrum (in ethanol): λ_{max} . at 287 to 288 m μ , $\epsilon=19,960$.

This compound is not described in the literature.

The preceding specific embodiments are illustrative of the invention. It is to be understood, however, that other expedients known to those skilled in the art, particularly utilizing the reactions involved on materials having an ethyl or an n-propyl in the 13 β position may be employed without departing from the spirit of the invention.

We claim:

1. A substituted des-A steroid of the formula

wherein R is an alkyl having from 1 to 6 carbon atoms, X is a member selected from the group consisting of hydrogen, alkyl having from 1 to 5 carbon atoms, alkenyl having from 3 to 5 carbon atoms, alkoxyalkyl having from 2 to 5 carbon atoms, and the acyl of an organic carboxylic acid having from 1 to 18 carbon atoms selected from the group consisting of saturated and unsaturated aliphatic carboxylic acids, saturated and unsaturated cycloaliphatic carboxylic acids, benzoic acid, cycloalkylalkanoic acids, phenylalkanoic acids, phenoxyalkanoic acids, furan-2-carboxylic acid, 5-t-butylfuran-2-carboxylic acid and β -ketoalkanoic acids.

2. The substituted des-A steroid of claim 1 wherein said R, an alkyl having from 1 to 6 carbon atoms, is selected from the group consisting of methyl, ethyl, propyl, isopropyl, butyl and isobutyl.

3. The substituted des-A steroid of claim 1 wherein R is methyl and X is benzoyl.

4. The substituted des-A steroid of claim 1 wherein R is ethyl and X is benzoyl.

5. The substituted des-A steroid of claim 1 wherein R is methyl and X is 2'-methylallyl.

6. The substituted des-A steroid of claim 1 wherein R is methyl and X is 3'-methyl-2'-butenyl.

7. A 17-ether des-A steroid of the formula

wherein R is an alkyl having 1 to 6 carbon atoms, X₁ is a member selected from the group consisting of alkylthioalkyl having from 2 to 5 carbon atoms, cycloalkyl having from 4 to 7 carbon atoms, cycloalkylalkyl having

from 4 to 11 carbon atoms, and phenylalkyl having from 7 to 11 carbon atoms.

8. The substituted des-A steroid of claim 7 wherein R is methyl and X is benzyl.

9. The substituted des-A steroid of claim 7 wherein R is methyl and X is hexahydrobenzyl.

10. The process for the production of a substituted des-A steroid of claim 1 which comprises the steps of formylating a des-A- Δ^9 -gonene of the formula

wherein R is an alkyl having from 1 to 6 carbon atoms, X is a member selected from the group consisting of hydrogen, alkyl having from 1 to 5 carbon atoms, alkenyl having from 3 to 5 carbon atoms, alkoxyalkyl having from 2 to 5 carbon atoms, and the acyl of an organic carboxylic acid having from 1 to 18 carbon atoms selected from the group consisting of saturated and unsaturated aliphatic carboxylic acid, saturated and unsaturated cycloaliphatic carboxylic acids, benzoic acid, cycloalkylalkanoic acids, phenylalkanoic acids, phenoxyalkanoic acids, furan-2-carboxylic acid, 5-t-butylfuran-2-carboxylic acid and β -ketoalkanoic acids, by the action of a formylating agent consisting of an N,N-di substituted formamide and an inorganic chlorination agent dehydrogenating the resulting 10-hydroxymethylene enone of the formula

wherein R and X have the above-assigned meanings, by the action of a dehydrogenating agent selected from the group consisting of halo-substituted p-benzoquinones, cyano-substituted p-benzoquinones and halo-cyano-substituted p-benzoquinones, reducing the resulting formyl dienone of the formula

wherein R and X have the above-assigned meanings, by the action of a metal hydride selected from the group consisting of an alkali metal borohydride and tri-t-butoxyaluminum-lithium hydride in the presence of a solvent media, and recovering said substituted des-A steroid.

11. The process of claim 10 wherein said N,N-disubstituted formamide is a member selected from the group consisting of dimethylformamide, N-methyl-N-phenylformamide and N-piperidino-N-methylformamide.

12. The process of claim 10 wherein said formylating step is effected by the action of the phosphorus oxychloride-dimethylformamide complex.

13. The process of claim 10 wherein said dehydrogenating agent is selected from the group consisting of 2,3 - dichloro-5,6-dicyano-p-benzoquinone, 2,3-dibromo-5,6 - dicyano - p-benzoquinone, 2,3-dibromo-5,6-dicyano-p - benzoquinone, 2,3,5,6 - tetrachloro-p-benzoquinone, 2,3 - dicyano - 5-chloro-p-benzoquinone and 2,3-dicyano-p-benzoquinone.

14. The process of claim 10 wherein said reducing step is effected by the action of an alkali metal borohydride selected from the group consisting of sodium borohydride and potassium borohydride.

15. The process for the production of a 17-ether des-A steroid of claim 1 which comprises the steps of formylating a des-A- Δ^9 -gonene of the formula

wherein R is an alkyl having 1 to 6 carbon atoms and acyl represents the acyl of an organic carboxylic acid having from 1 to 18 carbon atoms selected from the group consisting of saturated and unsaturated aliphatic carboxylic acid, saturated and unsaturated cycloaliphatic carboxylic acid, benzoic acid, cycloalkylalkanoic acids, phenylalkanoic acids, phenoxyalkanoic acids, furan-2-carboxylic acid, 5-t-butylfuran-2-carboxylic acid and β -ketoalkanoic acid, by the action of a formylating agent consisting of an N,N-di-substituted formamide and an inorganic chlorination agent, dehydrogenating the resulting 10-hydroxymethylene enone of the formula

wherein R and acyl have the above-assigned meanings, by the action of a dehydrogenating agent selected from the group consisting of halo-substituted p-benzoquinones, cyano-substituted p-benzoquinones and halo-cyano-substituted p-benzoquinones, reacting the resulting formyl dieneone of the formula

wherein R and acyl have the above-assigned meanings, with a ketalizing agent selected from the group consisting of 2-di-lower alkyl-dioxolanes and lower alkanediols, saponifying the resulting diketal of the formula

wherein R and acyl have the above-assigned meanings and K represents lower alkyleneoxy, etherifying the resulting 17 β -ol of the formula

15 wherein R and K have the above-assigned meanings, by the action of a halide of the formula

wherein Hal represents a halogen other than fluorine and X₁ is selected from the group consisting of alkylthioalkyl having from 2 to 5 carbon atoms, cycloalkyl having from 4 to 7 carbon atoms, cycloalkylalkyl having from 4 to 11 carbon atoms, and phenylalkyl having from 7 to 11 carbon atoms in the presence of a metal hydride and a polar solvent, hydrolyzing the resulting 17-ether of the formula

30 40 wherein R, X₁ and have the above-assigned meanings, by the action of an aqueous organic acid, reducing the resulting formyl dienone of the formula

35 50 55 wherein R and X have the above-assigned meanings, by the action of a mixed metal hydride selected from the group consisting of an alkali metal borohydride and tri-t-butoxy-aluminum-lithium hydride in the presence of a solvent media, and recovering said 17-ether des-A steroid.

UNITED STATES PATENT OFFICE
CERTIFICATE OF CORRECTION

Patent No. 3,766,248 Dated October 16, 1973

Inventor(s) Lucien Nedelec et al.

It is certified that error appears in the above-identified patent and that said Letters Patent are hereby corrected as shown below:

Column 1, line 12, The claim of priority should read as follows:

France P.V. 43,565 December 23, 1965
France P.V. 116,922 August 4, 1967
France P. V. 117,736 August 11, 1967

Column 1, line 55, "Reference to Prior Applications" should read -- This application is a continuation-in-part of our copending applications Serial No. 603,094, filed December 20, 1966, now abandoned, and Serial No. 728,880, filed May 14, 1968, now U. S. Patent No. 3,574,688, this later application being a continuation-in-part of Serial No. 603,457, filed December 21, 1966, and now abandoned. Column 8, line 8, Formula VII, should appear as shown below:

Column 9, line 57, "a- $\Delta^9(11)$ " should read -- $\Delta^9(11)$ --.

Column 14, lines 23 and 24, "atmospheric" should -- atmosphere --; line 36, "nirtogen" should read -- nitrogen --. Column 16, line 58, "-res-" should read -- -des- --.

UNITED STATES PATENT OFFICE
CERTIFICATE OF CORRECTION

Patent No. 3,766,248 Dated October 16, 1973

Inventor(s) Lucien Nedelec et al.

It is certified that error appears in the above-identified patent and that said Letters Patent are hereby corrected as shown below:

Column 19, lines 4 and 5, cancel "2,3-dibromo-5,6-dicyano-p-benzoquinone"; line 16, the formula in claim 15, should appear as shown below:

line 49, "dienon" should read -- dienone --.

Signed and sealed this 24th day of September 1974.
